UNITED STATES PATENT OFFICE

NETTIE M. ELBON, OF CHARLESTON, WEST VIRGINIA

RACK

Application filed July 26, 1928. Serial No. 295,610.

This invention is a device primarily designed for use in connection with the conducting of juvenile tooth brush drills and the like, although not limited to this particular 5 use.

It is now common practice in the public schools to strongly emphasize the importance of dental hygiene, and tooth-brush drills have become a part of the daily school routine in 10 many localities. However, the effectiveness of such drills is often impaired and proper instruction hampered, to say nothing of insanitary conditions being created, by the lack 15 of proper and convenient facilities for catching and disposing of the saliva, water, etc. expelled from the mouths of the children during such drills. The effective disposal of this refuse is necessary and important not only for sanitary reasons, but also to prevent 20 untidy conditions in the school room, or other quarters where the instruction is being given.

One of the objects of the invention is to provide a supporting rack, which may be placed in any desired position in a school 25 room, so that the children may be conveniently assembled about it for the desired tooth-brush drills. A further object is to provide a stand of the character mentioned, constructed so that it may be collapsed or 30 folded into compact form, for convenient storage when not required.

The invention will be hereinafter fully set forth and particularly pointed out in the claims.

35 In the accompanying drawing:—

Figure 1 is a side elevation illustrating a rack constructed in accordance with the invention. Figure 2 is an end view thereof. Figures 3 and 4 are similar views respectively illustrating the rack in collapsed condition.

Referring to the drawings, A and A' represent two end frames or uprights each consisting of side bars 10, rigidly connected 45 at their lower portions by a cross bar 11, and near the upper portion by a second cross bar 12, which serves as a trough support.

The parts thus far described are shown as 50 constructed of flat metal. The lower ends of the bars 10 extend below the plane of the

cross bar 11 and diverge outwardly, their extremities being bent as indicated at 13 to provide supporting feet. Projecting above the plane of the bar 12 are trough engaging arms 14, which diverge upwardly and outwardly, as shown. 55

The uprights A and A' are connected by side bars 15, the extremities of which are movably connected to the side bars by pivots 16, at positions preferably immediately above 60 the plane of the cross bars 11. Said side bars 15 are connected with the side members 10 of the uprights by means of brace members B. Each brace member consists of two members 17 and 18 pivotally connected together at one end, as indicated at 19, the other end of the member 17 being pivoted to a side bar 15, as indicated at 20. The other end of the member 18 is offset, as indicated 65 at 21 and pivoted to a side 10 of one of the uprights, as indicated at 22. It will be noted that the uprights A and A' are wider at the bottom than at the top, and that the offset 21 is provided so that the member 18 will lie approximately over the adjacent side bar 70 15 when the rack is in open position. Each member 17 of the brace members is provided with a flange 23, which engages the adjacent portion of the member 18, to limit the relative 75 pivotal movement of the arms 17 and 18. 80

It is preferred to use but two of the braces B. The member 18 of one brace is secured to a side member of an upright A and the member 17 of said brace being connected to the adjacent side bar 15. The member 18 of the 85 other brace is secured to a side member 10 of the upright A', but on the other side of the rack. And the arm 17 of said brace is connected to the adjacent side bar 15. Thus, but one brace member is employed for each 90 upright, the two brace members being located on opposite sides of the rack.

Located between the arms 14 of the two uprights, and resting upon the cross bars 12 thereof is a trough T, which may, if desired, 95 be provided with a discharge opening 24 in its bottom wall, normally closed by a plug 25.

In practice, it is preferred to construct the parts of the rack of flat metal strips, as 100 shown, although the invention is not limited

in this particular. When it is desired to employ the rack, for instance, to support the trough T for a tooth brush drill, the upper ends of the rack while in folded position (Figures 3 and 4) are grasped by the operator and drawn apart. The uprights will hinge upon the pivots 16 of the side bars 15, and their upper ends may be moved outwardly until stopped by means of the brace members 10 B, which automatically unfold and take the positions illustrated in Figure 1, the separating movement of the uprights being limited by the stops 23. The trough T may then be placed upon the cross bars 12 and between 15 the arms 14, after which the pupils may gather around and go through the desired drill in any manner which may be directed by the instructor. The trough is so supported that it will conveniently catch the saliva, 20 water, etc., expelled from the mouths of the children during the drills, so that they may be conveniently disposed of at a subsequent time, preferably immediately after the drill is over. When there is no further use for the 25 trough and rack, the trough is removed and cleansed in any desired sanitary manner, and the rack is folded by bringing the upper ends toward each other, so that the brace members B will fold upon their pivots 19, the parts 30 assuming the positions illustrated in Figures 3 and 4.

The advantages of the invention will be readily apparent to those skilled in the art to which it belongs. For instance, an important advantage is that a very compact and inexpensive stand or rack is provided, by means of which a trough may be rigidly supported in a position to permit of the convenient assembly of children around it for tooth brush drills. It will also be observed that the stand is exceedingly simple and inexpensive in construction, and may be readily folded and conveniently stored when not required. Yet, whenever required, it may be 45 quickly assembled and placed in any convenient position on the floor of the school room.

It is to be understood, that although the invention has been specifically described as applicable for use in the conducting of tooth brush drills, it is not limited to such use, but obviously may be employed in various other ways and for many different purposes without departing from the spirit of the invention.

Having thus explained the nature of the invention and described an operative manner of constructing and using the same, although without attempting to set forth all of the forms in which it may be made, or all of the 60 forms of its use, what is claimed is:—

1. A trough-supporting rack of the character described comprising two spaced apart end members each having a trough-supporting cross bar near its top and spaced apart engaging arms projecting above the plane

of said cross bar, side bars having their extremities pivotally connected to the lower portions of said end members, and brace members each consisting of two pivotally connected arms, one of said arms having an end pivotally connected to an end member, and the other arm having an end pivotally connected with an adjacent portion of a side bar, so that the arms of said brace members will be in alignment with each other while the 75 end members are in an upright position. 70

2. A trough-supporting rack of the character described comprising two spaced apart end members formed of flat metal strips, each having a trough-supporting cross bar near its top and spaced apart diverging trough engaging arms projecting above the plane of said cross bars, each member also having legs depending below its cross bar, the lower extremities of said legs being offset 80 to provide feet, two side bars having their extremities pivotally connected to sides of said end members near the lower ends thereof, and two brace members one at each end of the rack but on opposite sides thereof, each brace 85 member consisting of two pivotally connected arms, one of said arms having an end pivotally connected to the side of an end member and the other arm having an end pivotally connected with an adjacent portion of a 90 side bar, so that the arms of said brace members will be in alignment with each other while the end members are in an upright position. 95

3. A trough supporting rack of the character described comprising two spaced apart end members each having a trough supporting cross bar near its top and spaced apart diverging trough engaging arms projecting above the plane of said cross bar and diverging laterally, 100 said end members having legs which diverge laterally below said cross bar, side bars having their extremities pivotally connected to the legs of said end members, and brace members each consisting of two pivotally connected arms one of which is offset at 105 one end, said offset end being pivotally connected to a leg of an end member, and the other arm having an end pivotally connected with an adjacent portion of a side bar, so that 110 said arms will be in approximate alignment while in open position, the last mentioned arm having a stop flange positioned to engage the first mentioned arm of the brace so as to 115 maintain said alignment while the end members are in upright position. 115

In testimony whereof I have hereunto set my hand.

NETTIE M. ELBON.
